AERATION TUNNEL FOR STORAGE BINS

James A. Watkins, 2501 Harmony, Amarillo, Tex.

Filed June 13, 1961, Ser. No. 65,577

Term of patent 14 years

(Cl. D13—1)

FIG. 1

FIG. 2

FIG. 3

FIG. 4

FIG. 5

FIGURE 1 is a front perspective view of an aeration tunnel for storage bins showing my new design;

FIGURE 2 is an enlarged perspective view of the front left central portion shown in FIGURE 1 showing details of the invention.

FIGURE 3 is a side elevational view thereof;

FIGURE 4 is a top plan view thereof; and

FIGURE 5 is a diametral cross-section through plane 5'-5" of FIGURE 4.

I claim:

The ornamental design for an aeration tunnel for storage bins, as shown.
